UNITED STATES PATENT OFFICE.

JOSHUA K. INGALLS, OF BROOKLYN, NEW YORK, ASSIGNOR TO M. H. HOWELL, OF NEW YORK, N. Y.

METAL BEAM.

Specification of Letters Patent No. 15,113, dated June 10, 1856.

To all whom it may concern:

Be it known that I, JOSHUA K. INGALLS, of the city of Brooklyn, county of Kings, and State of New York, have invented a 5 new and useful Method of Constructing or Making Metal Beams; and I hereby declare the following to be a full and clear description of the same, reference being had to the accompanying drawings, making a part 10 of this specification, in which—

Figure 1, represents a side view in perspective; Figs. 2 and 3, side elevations.

A is a top flanch; B, a corrugated web, and C a bottom flanch, truss, or tie, and a 15 is a cross tie or bolt, and b is a cross section.

It has long been known that cast iron possesses in the ratio of cost of material one requisite of strength even in a superior degree to wrought iron, while its capacity to 20 resist tension is greatly inferior. Now, as in any beam, the top portion is compressed and the bottom portion strained, by any load, it should appear that the top flanch ought to be made of cast iron and the bottom flanch of wrought iron. But heretofore no successful method has been found of trussing cast iron beams, inasmuch as the inflexible nature of the cast iron and the more yielding qualities of the wrought iron 25 caused the cast iron to be ruptured before the wrought iron had come to its full tension.

The nature of my invention consists in furnishing any metal beam, with a web corrugated in its length, in such a manner as to unite the top flanch, or strut, or arch, with the bottom flanch, or truss, or tie. 35

To enable others skilled in the use of iron for similar purposes to make my beam, I 40 will further describe my method.

First, I make a cast iron beam with top flanch, A, and corrugated web B as shown in Fig. 1, said corrugations having the greatest lateral extent at the bottom, and 45 receding toward the top, until the web becomes nearly or quite straight, where it attaches to the top flanch. The ends of this beam I provide with stout flanches cast upon the bottom of the web, with grooves 50 to receive the T heads of the wrought iron

tie, as shown at T. I then provide a wrought iron bottom flanch or tie, c, and secure the ends with T heads in the cast iron end flanches in a manner similar to that in which the bow string beam in common use, is made, or by bolts or any other convenient method. I then further secure the top and bottom flanches, by means of bolts or ties, a, a. Also, I make a beam as shown by Fig. 2 with the top flanch and 55 web of cast iron as above described, the web on the bottom being terminated by an inverted arc, parabolic or catenary line, and furnished with a wrought iron truss as shown. Again, I make the beam entirely 60 of cast metal, making the corrugations extend most in width in the middle of the web, and receding to right lines at top and bottom where it attaches to the flanches, as 65 shown in Fig. 3.

The advantage of my invention consists in the corrugated web, which enables me to combine the cast and wrought materials in such a manner as to cause them to act simultaneously in every moment of depression, 70 until the one is crushed or the other broken. The flexibility of the corrugated web allows the cast metal to yield until the wrought iron is brought to its full tension; the form at the same being much better calculated to 75 secure the beam from collapsing or tearing, and can therefore be made much lighter than the ordinary rigid web. It enables me to overcome the difficulty heretofore experienced, in shrinking on the ties to cast 80 iron beams, by which means a considerable portion of the strength of the materials is exhausted before it receives any load at all.

Having therefore described my invention, I am aware that a wrought iron beam has 85 been made with wrought iron, corrugated web, said "corrugations resisting compression in the direction of their length"; I do not therefore claim that; but

What I do claim and desire to secure by 90 Letters Patent is—

1. The corrugated web, when cast with or upon the top flanch, and arranged with the bottom flanch or tie, in such manner as to afford flexibility to the cast portion of 100

the beam, to accommodate its action to the tension of the wrought portion, in the manner set forth.

2. I claim the tapering form of the corrugations in their height, which gives a right line, where the web attaches to the top flanch, with which it acts in resisting compression; and which increases the breadth

of said corrugations, and consequently the flexibility of the web, where it touches the bottom flanch or tie, with which it acts in resisting extension.

JOSHUA K. INGALLS.
